United States Patent Office

Des. 229,711
Patented Dec. 25, 1973

229,711

LAMP FIXTURE

Richard B. Poff, 743 N. Main St., Auburn, Ind. 46706

Filed Dec. 13, 1971, Ser. No. 207,727

Term of patent 14 years

Int. Cl. D26—05

U.S. Cl. D48—23 R

FIG.1

FIG.2

FIG. 3

FIG. 4

FIG. 5

FIG. 1 is a side elevational view of a lamp fixture showing my new design;

FIG. 2 is a top plan view thereof;

FIG. 3 is an end elevational view thereof;

FIG. 4 is a bottom plan view thereof; and

FIG. 5 is a perspective view thereof on a reduced scale. The canopies are omitted and the chains fragmentarily shown in FIGS. 1, 2 and 3 for convenience of illustration.

I claim:

The ornamental design for a lamp fixture, as shown and described.
